MACHINE FOR OPERATING UPON SHOES

Charles G. Brostrom, Salem, Mass., assignor to
United Shoe Machinery Corporation, Borough
of Flemington, N. J., a corporation of New
Jersey

Application December 8, 1938, Serial No. 244,631

10 Claims. (Cl. 12—30)

This invention relates to machines for operating upon shoes and is herein illustrated and described as embodied in a machine for opening channels formed upon shoe soles. The usual practice in the opening of channels is to present the shoe by hand to the operating instrumentalities, beginning at one end of the channel and feeding the shoe progressively until the entire channel has been opened. The shoe is thus presented, for example, in using the machine disclosed in United States Letters Patent No. 2,076,698, granted April 13, 1937 upon an application filed in my name, which machine is provided with channel opening instrumentalities similar to those disclosed herein.

It is an object of the present invention to provide an improved channel opening machine having facilities for assisting the operator in presenting the shoe to the channel opening instrumentalities. In accordance with a feature of the invention the illustrated machine is provided with means engageable with the shoe upper for feeding the shoe relatively to the operating instrumentalities and with yielding means for holding the feeding means against the shoe upper. The feeding means herein illustrated consists of a roll which may be of rubber and which may be tapered to clear the edge of the sole. This roll is held against the shoe upper by a spring, and provision is made for enabling the roll to yield both upwardly and downwardly from a desired heightwise position. The illustrated machine is further provided with an abutment engageable with the toe end of the sole for facilitating the turning of the sole during operation upon portions of the channel adjacent to the toe end. This abutment in the illustrated machine comprises a post engageable with the edge of the sole and yieldable laterally of the direction in which the sole is fed but which is held rigidly against movement in the direction of feed to enable the post to serve as a fulcrum about which the toe end of the shoe may be turned.

The invention further consists in various features of construction and combinations and arrangements of parts herein shown and claimed, the advantages of which will be apparent to those skilled in the art from the following description, reference being had to the accompanying drawings, in which

Fig. 1 is a side elevation of the improved machine;

Fig. 2 is a vertical sectional view taken along the line II—II of Fig. 4;

Fig. 3 is an enlarged view in side elevation of a portion of a machine;

Fig. 4 is a plan view of the machine;

Fig. 5 is a plan view of the operating instrumentalities;

Fig. 6 is a plan view illustrating the operation of the machine upon a shoe; and

Fig. 7 is a plan view illustrating the operation with the shoe in a less advanced position than shown in Fig. 6.

The operating members of the improved machine comprise a pair of tools 10 and 12 (Fig. 4) arranged in side-by-side relation to each other. These tools, which are reciprocated alternately, are shown in Figs. 6 and 7 as operating upon a shoe S upon the outsole of which is formed a channel lip L. The tool 10 has an end portion 14 (Fig. 1) adapted to raise the lip L, the end portion 14 being concave in a direction heightwise of the sole and convex in a direction lengthwise of the sole. The tool 12 (Fig. 2) has a downwardly extending nose which strikes against the shoulder of the turned lip and an upwardly inclined under surface 16 which performs an ironing operation to set the raised and partially turned lip. The tool 12 has an extension 18 which increases the bearing area of the under surface 16. Beneath the tools 10 and 12 and bearing against under surfaces formed on said tools is a thin blade-like gage 20 adapted to enter the channel and to engage the root of the channel lip L, otherwise known as the shoulder of the channel, to position the shoe in proper relation to the tools 10 and 12. The gage 20 is not stationary but is oscillated lengthwise of the channel to facilitate feeding of the work. As the tools 10 and 12 are reciprocated the tool 10 will first engage the channel lip to raise it to upstanding position. The tool 12 which is already in engagement with a previously turned portion of the lip will then advance into engagement with the newly raised portion of the lip and turn it back to set the lip.

The operating mechanism for the above-mentioned tools is housed in a hollow head 22 having a cover plate 21 and supported by a column 23 adapted to rest upon the floor. Journaled in the head 22 is a shaft 24 (Fig. 4) upon which is secured a pulley 26 adapted to be driven from any suitable source of power. Secured within the housing 22 are two upright posts 28 and 30. An arm 32 is fulcrumed at its central portion upon the post 28 and an arm 34 parallel to the arm 32 is fulcrumed at its central portion upon the post 30. A link 36 which is substantially parallel to the line joining the centers of the posts 28 and 30 is pivotally secured to the ends of the arms 32 and 34 upon one side of said center-line. A similar link 38 is pivotally secured to the opposite ends of the arms 32 and 34. The link 36 extends out through an opening in the housing 22 and at its outer end portion carries an extension 37 (Fig. 5) upon which is mounted the tool 12 while the link 38 similarly extends out through the opening in the housing and at its outer end carries an extension 39 upon which is

mounted the tool 10. The tools 10 and 12 are secured by pivot pins 40 for heightwise swinging movement to the extensions 39 and 37 of their respective carrier links and are pressed downwardly by leaf springs 42 to stop positions determined by the engagement of the under surface of each tool with an extended portion of its carrier. The link 38 has an extension 44 beyond the arm 34. Secured upon the shaft 24 is an eccentric 46 upon which is mounted an eccentric strap 48 which constitutes an end portion of a connecting rod 50, the opposite end of the connecting rod 50 being connected by a universal coupling to the extension 44. It is evident that the above-described arrangement will provide for parallel movement of the arms 36 and 38 and hence of the tools 10 and 12 alternately in opposite directions.

The gage 20 is pivotally mounted upon a bearing pin 52 (Figs. 2 and 5) secured in a sliding block 54 which is mounted in a block 56 with provision for adjustment of the gage 20 in the direction of movement of the tools 10 and 12. The block 56 in turn is secured upon a block 58 with provision for heightwise adjustment and the block 58 is secured upon the head 22 with provision for horizontal adjustment of the gage 20 in a direction normal to the direction of the movement of the tools 10 and 12. The gage 20 has a tail portion 60 extending beyond the pin 52 upon the end portion of which is pivotally mounted a block 62 which is embraced by a fork 64 extending from the arm 32. A bolt 61 adjustably threaded in a bracket 63 secured to the housing 22 has a head having a smooth surface which bears against the upper surface of the tail 60 to support the gage 20 against any tendency to tilt vertically. It is evident that the rocking of the arm 32 about the post 28 as the tools 10 and 12 reciprocate will serve also to rock the gage 20 about the pin 52.

The operating mechanism as so far described is identical with that disclosed in the above-mentioned Letters Patent No. 2,076,698. The tools 10 and 12 and the gage 20 disclosed herein are similar to the corresponding members shown in said Letters Patent, being designed, however, for operation upon channels of the English type.

For feeding the shoe S past the operating tools there is provided a frusto-conical rubber roll 66 having a rounded periphery engageable with the shoe upper. The roll 66 (Fig. 2) has a metal hub 68 which is journaled upon an upstanding pin 70 secured in a block 72 which, in turn, is secured to a block 74. Extending horizontally through the upper portion of a housing member 73 secured by screws 75 to the cover plate 21 is a pin 76 from the outer end portions of which depend a pair of swinging arms 78 (Figs. 1, 2, 4 and 7) upon opposite sides of the member 73. As shown in Fig. 4, slots for the screws 75 are provided in the cover 21 to enable the member 73 to be adjusted to the right or left. Pivotally mounted upon the lower ends of the arms 78 is a bracket 80 upon which is adjustably secured by screws 82 the block 74. Formed upon the hub 68 is a bevel gear 83 which is driven by a bevel gear 84 secured upon a shaft 86 journaled in the block 74. The shaft 86 is driven in the direction indicated by the arrow in Fig. 6 through an intermediate shaft 88 by a shaft 90 which is journaled for longitudinal sliding movement in the head 22, the shaft 88 being connected for universal movement to the shafts 86 and 90. A pinion 92 (Figs. 1 and 4) secured on the shaft 90 is driven through a

pair of intermeshing gears 94 and 96 by a shaft 98 upon which is secured a worm wheel 100. A worm 102 secured upon the shaft 24 drives the worm 100. This arrangement provides for driving the feed roll 66 at a speed very much less than that of the shaft 24.

The roll 66, as above described, is free to rise and fall about the pivotal connection of the bracket 80 to the arms 78 and is free to move in the direction of movement of the tools 10 and 12 by reason of the pivotal connection of the arms 78 to the head 22. To control the position assumed by the roll 66 the arms 78 are urged toward the left, as viewed in Fig. 1, by a pair of springs 104 (Figs. 1 and 4) operating against the respective arms. Welded upon each side of the housing member 73 is a bracket 106 (Figs. 1 and 4) having a lug 108 which constitutes an abutment for the respective springs 104. Each of the brackets 106 has a lug 110 through which is threaded a stop screw 112 for adjustably limiting the forward swing of the respective arms 78 and thus limiting the movement of the roll 66 toward the left, as viewed in Fig. 1.

The heightwise position of the roll 66 is controlled by a pin 114 (Figs. 2, 3 and 7) secured in the bracket 80 and slidably engaging a horizontal groove 116 formed in a block 118. A pair of rods 120 secured at their upper ends to an extension 122 of one of the brackets 106 and connected at their lower ends by a block 124 constitute a support upon which the block 118 is freely slideable up and down. Interposed between the extension 122 and the block 118 is a spring 126, while interposed between the block 124 and the block 118 is a spring 128. The springs 126 and 128 are centered and supported by a rod 130 secured in the extension 122 and block 124 and passing freely through the block 118. The block 118 will tend to maintain a neutral position under the influence of the springs 126 and 128, from which position, however, it may yield either upwardly or downwardly.

Secured upon the brackets 106 is a platform 131 (Figs. 1, 2 and 4) upon which is secured a block 132. Fulcrumed upon a pin 134 mounted in the block 132 is a block 136 in which is rigidly secured a downwardly extending post 138. A tension spring 140 interposed between the block 136 and a support 142 on the platform 131 tends to swing the post 138 toward the left, as viewed in Fig. 1, to a stop position adjustably determined by a screw 144 threaded through a lug in the block 136 and engageable with the upper surface of the block 132. The post 138 is vertical or substantially so, as may be desired and may yield toward the right, as viewed in Fig. 1.

In the operation of the machine the shoe S having a channeled sole is presented by hand to the operating tools. The lip L is turned over by hand at a locality adjacent to one end of the channel and the shoe is presented with the tool 12 extending over the turned-over portion of the lip and with the gage 20 extending into the channel. The operator presses the shoe upwardly and toward the right, as viewed in Fig. 2, against the gage 20 with the root of the lip L in contact with the end of the gage. When the shoe is in this position the feed roll 66 will be held in engagement with the upper of the shoe by the springs 104, the roll 66 having yielded to the right from its normal stop position. The feed roll not only is yieldingly held against the upper by the springs 104, but is enabled also by the springs 126 and 128 to yield up or down. Such provision for

heightwise yielding is important because of the fact that ordinary soles are not plane and have to be tilted up or down as the junction of the shank with the forepart passes the operating tools. The post 138 will press idly against the edge of the sole, having likewise yielded to the right from its normal stop position. As the tools 10 and 12 reciprocate alternately the tool 10 will raise the lip L and the tool 12 will set the lip. As the operation progresses toward the toe end of the shoe the post 138 under the influence of the spring 146 will follow the curvature of the edge of the sole at the toe end, swinging gradually to the left until it occupies its normal stop position shown in Fig. 7. As the operator turns the shoe at its toe end the post 138 serves conveniently as a fulcrum to facilitate the swinging of the shoe. As the operation passes the portion of greatest curvature and the shoe is again presented laterally to the operating tools the post 138 will yield to the right as shown in Fig. 6 and thus will not in any way interfere with the feeding of the shoe.

Having thus described my invention, what I claim as new and desire to secure by Letters Patent of the United States is:

1. A machine for operating upon shoes comprising means for operating upon a channel formed on the sole of a shoe, a roll engageable with the shoe upper, means for holding said roll in a desired heightwise position from which said roll may yield both upwardly and downwardly, and means for driving said roll to feed the shoe relatively to said operating means.

2. A machine for operating upon shoes comprising means for operating upon a channel formed on the sole of a shoe, a roll engageable with the shoe upper, a pair of opposed springs acting upon said roll for holding said roll in a desired heightwise position from which said roll may yield both upwardly and downwardly, a spring urging said roll against the shoe upper, and means for driving said roll to feed the shoe relatively to said operating means.

3. A channel opening machine comprising means for opening a channel formed on the sole of a shoe, a roll engageable with the shoe upper, a carrier in which said roll is rotatably mounted, an arm upon which said carrier is pivotally mounted for substantially heightwise swinging movement of said roll, a support upon which said arm is pivotally mounted for substantially horizontal swinging movement of said carrier, yieldable means for maintaining said carrier in a desired position both heightwise and horizontally with respect to said channel opening means, and means for driving said roll to feed the shoe relatively to said channel opening means.

4. A channel opening machine comprising means for opening a channel formed on the sole of a shoe, a roll engageable with the shoe upper, a carrier in which said roll is rotatably mounted, a support for said carrier constructed and arranged to enable said roll to move both vertically and horizontally, a vertical guide, a slide on said guide, a pair of opposed springs acting upon said slide for maintaining said slide in a desired heightwise position from which the slide may yield both upwardly and downwardly, a connection between said carrier and said slide for controlling the heightwise position of said carrier in accordance with the heightwise position of the slide, said connection being constructed and arranged for horizontal movement of said carrier relatively to said slide, a spring for urging the roll horizontally against the shoe upper, and

means for driving said roll to feed the shoe relatively to said channel opening means.

5. A channel opening machine comprising means for opening a channel formed on the sole of a shoe, a roll engageable with the shoe upper, means for driving said roll to feed the shoe relatively to said channel opening means, a gage for gaging the shoe in relation to said channel opening means, a support for said feed roll, and a spring acting upon said support to urge said roll against the shoe while enabling the roll to yield under pressure of the shoe as the shoe is held against said gage.

6. A channel opening machine comprising means for opening a channel formed on the sole of a shoe, a roll engageable with the shoe upper, means for driving said roll to feed the shoe relatively to said channel opening means, a gage for gaging the shoe in a direction transverse to the direction in which the shoe is fed by said feed roll, a support constructed and arranged to enable said roll to yield under pressure of the shoe both heightwise and transversely of the direction in which the shoe is being fed, and resilient means for holding said roll against the shoe. 25

7. A channel opening machine comprising a pair of reciprocating tools constructed and arranged to raise a channel lip on the sole of a shoe and to turn back the lip respectively, means for reciprocating said tools, a driven feed roll engageable with the shoe upper, and a spring for holding said roll against the shoe as the shoe is presented by hand to said lip-raising tools. 30

8. A channel opening machine comprising a pair of reciprocating members in side-by-side relation constructed and arranged to raise a channel lip on the sole of a shoe and to turn back the lip respectively, a thin blade-like gage adapted to enter the channel and against which the shoulder of the lip may be held, a driven feed roll engageable with the upper of the shoe, and yieldable means for holding said roll against the shoe, said holding means being also constructed and arranged to yield heightwise of the shoe. 40

9. In a machine for operating upon the soles of shoes, means for operating progressively upon the marginal portion of a sole when the shoe is presented by hand, a post engageable with the edge of the sole as the shoe is being fed, and a support for said post constructed and arranged for yielding movement of the post laterally of the direction of feed while holding said post rigidly against movement in the direction of feed to enable the post to facilitate turning of the shoe during operation in the vicinity of the toe end of the sole. 55

10. In a machine for operating upon channels formed upon the soles of shoes, means for operating progressively upon the channel of a sole when the shoe is presented by hand, means for feeding the shoe relatively to said operating means, a post engageable with the edge of the sole as the shoe is being fed, a pivotal support constructed and arranged for swinging movement of said post laterally of the direction of feed while holding said post rigidly against movement in the direction of feed, a spring for urging said post against the edge of the sole, and a stop for limiting the movement of said post under the influence of said spring, said post being urged to its limiting position by said spring as the operation approaches the toe end of the sole to facilitate turning the shoe about the toe end. 65
